UNITED STATES PATENT OFFICE

2,506,860

TRAVELING SCAFFOLD

Samuel Dimon, Los Angeles, Calif.

Application February 20, 1947, Serial No. 729,851

1 Claim. (Cl. 304—9)

1

The present invention comprises novel and useful improvements in a traveling scaffold and more specifically pertains to a portable platform for use by painters, paper hangers and like craftsmen in order to facilitate their access to ceilings, walls or the like for work thereon.

The principal objects of this invention reside in providing a scaffold of the character above set forth which shall be of light weight construction; readily adjustable for various heights; which will provide convenient shelves for storing articles and materials required by the worker; which shall be provided with an improved mechanism for propelling the same by the worker without leaving his position upon the platform thereof; which shall be provided with a novel mechanism for steering the same during the aforementioned movement; wherein a manually operated single means is provided for both propelling and steering the device; wherein the propelling means is carried entirely by the steering mechanism and readily accessible to the worker; and wherein the common steering and propelling means may be vertically adjustable in conformity with adjustment of the platform for supporting the worker, as required.

Further important objects of the invention reside in providing a device in accordance with the preceding objects, which shall be of simple and sturdy construction, inexpensive to manufacture, dependable and durable in operation and which will be highly efficient for the purposes intended.

These, together with various ancillary objects of the invention which will later become apparent as the following description proceeds, are attained by this device, one embodiment of which has been illustrated by way of example only in the accompanying drawings, wherein:

Figure 1 is a perspective view of the traveling scaffold, the position of a worker thereon being indicated in dotted lines;

Figure 2 is a vertical sectional detailed view through the apparatus being taken substantially upon the section line 2—2 of Figure 3;

Figure 3 is a vertical transverse sectional view taken at right angles to that of Figure 2 and taken substantially upon the section line 3—3 of Figure 2;

Figure 4 is a detail view taken in horizontal section upon the line 4—4 of Figure 3 and illustrating the arrangement and construction of the steering wheels of the device;

Figure 5 is a fragmentary detail view of one of the fixedly supported wheels of the device and

2

taken substantially upon the section line 5—5 in horizontal section thereon;

Figure 6 is an enlarged fragmentary perspective view illustrating the construction and mounting of the common control means for propelling and steering the device; and,

Figure 7 is an enlarged fragmentary perspective view showing the steering and driving connection with a steering wheel of the device.

10 Referring now more specifically to the attached drawings, wherein like numerals indicate similar parts throughout the various views, attention is first directed chiefly to Figure 1 wherein it may be seen that the device indicated generally at 10 consists of a supporting frame work indicated generally at 12 and composed of suitable standards, reinforcements and cross bracing to form a rigid framework of either metal, wood or other materials or combinations thereof

20 as desired.

This supporting frame work is provided with a platform 14 which is intended to support in convenient position thereon a worker as indicated in dotted lines in Figure 1, this platform being suitably braced and supported from the four corner standards of the apparatus and being vertically adjustable thereof as by means of a series of longitudinally spaced holes in said standards with which the platform and braces

30 are adapted to be selectively engaged in a known manner.

As shown more clearly in Figure 2, the upper end of the supporting frame which is preferably in the form of a tower, is provided with 35 laterally extending arms 16 rigidly secured thereto between which arms are adapted to be positioned a pair of shelves 18 or the like for the reception of various materials employed by the worker. It may be here noted that the arms

40 16 and shelves 18 may be of any suitable dimensions, and when the device is to be employed by a painter, these shelves and arms are adapted to support a drop cloth or canvas which may thus be held in position beneath the surface 45 being painted, thus eliminating the necessity for laboriously placing and removing drop cloths and canvases in accordance with the previous practice.

As shown more clearly in Figures 1 and 5, one 50 end of the face of the supporting frame journals a transversely disposed axle 20 upon which are rotatably retained a pair of supporting wheels 22 of any suitable construction and in any desired manner.

The other end of the base of the supporting

framework has pivotally connected thereto a pair of steering wheels 24 and 26, the latter also constituting a propelling wheel in a manner to be set forth hereinafter. As shown more clearly in Figures 2 and 4, the wheel 24 which constitutes merely a steering wheel is retained in any suitable manner for rotation upon the laterally extending axle 28 of the vertically disposed arm or pin 30 which is journaled in any suitable part of the framework. The arrangement is such that the axle 28 and wheel 24 are free to swivel or turn about the vertical spindle or axle 30 in a manner to be subsequently set forth.

The steering shaft comprising upper and lower telescoping sections 32 and 34 respectively is vertically disposed and journaled in supporting brackets 36 from one of the corner standards of the supporting frame 12. As shown best in Figure 6, the sections 32 and 34 are retained in non-rotatable, longitudinally fixed predetermined position as by means of a fastening pin 38, it being understood that a plurality of apertures may be provided in one of these elements for longitudinally adjusting the telescoping members relative to each other. The upper and lower extremities of the steering shaft sections 32 and 34 are provided with laterally extending cranks 40 and 42 respectively.

The steering wheel 26 is rotatably journaled and retained upon the lower crank 42, whereby when the upper crank 40 is rotated in its support bracket by a means to be later set forth, the steering wheel 26 may be similarly pivoted for steering the apparatus.

Attention is now directed particularly to Figure 4, where it may be seen that the spindles 28 and 42 constituting axles for the steering wheels 24 and 26 respectively, are provided with laterally extending arms 46 and 44 respectively which are connected by means of a tie rod 48 of any suitable construction, whereby upon pivotal movement of the steering wheel 26, simultaneous and similar movement will be imparted to the other steering wheel 24 in a known manner.

A hand wheel 50 is journaled upon the upper crank 40 and has rigidly secured thereto a sprocket wheel 52, while the steering and propelling wheel 26 has a similar sprocket 54 rigidly carried thereby. A suitable sprocket chain 56 is entrained over the sprockets 52 and 54, whereby rotation of the hand wheel 50 will cause rotation of the propelling wheel 26, thereby producing movement of the apparatus. It should be here noted that the hand wheel 50 will be disposed in proper position to the platform 14 to permit even manipulation of the hand wheel by the worker from his position upon said platform, and it will be further noted that the weight of the worker will necessarily be disposed substantially above the traction wheel 26 when the latter is being rotated.

Further, by means of manipulation of the same wheel 50, the steering shaft sections may be rotated in their journals, and through the linkage 44, 46 and 48, will cause the two steering wheels 24 and 26 to assume a desired position to permit ready

maneuvering of the device. Thus, a single control means has been provided, whereby propulsion of the device and steering thereof may be effected by the worker without leaving his working platform. Moreover, the propelling means is entirely carried by the steering shaft, so that regardless of the rotation of the latter, the propelling means is constantly available for employment by the worker.

Since various modifications of the principles of this invention will be readily apparent to those skilled in the art after consideration of the foregoing specification and accompanying drawings, it is not desired to limit the invention to the exact construction shown and described, and all suitable modifications and equivalents falling within the scope of the appended claims may be resorted to.

For example, although the device has been shown as employing two steering wheels, it will be readily understood that in some instances the connecting linkage 44, 46 and 48 may be omitted, whereby the wheel 24 will constitute a freely swiveling caster, and steering and propulsion of the device may be effected and controlled solely by the wheel 26. In other instances, it may be preferred to employ but a single wheel at the steering end of the scaffold, in conjunction with a pair of rear wheels 22.

What I claim is:

A traveling scaffold comprising a frame and a platform carried thereby, said frame including opposed pairs of spaced L-shaped stud members, a plurality of horizontally extending L-shaped beam members secured to said stud members, a vertical shaft journaled in said beam members, an upper work table comprising a plate secured to the upper ends of said stud members and having a central opening therethrough permitting an operator to stand therein, supporting wheels journaled on said frame, upper and lower crank arms secured to said shaft, a combination drive steering and supporting wheel journaled on said lower crank arm, a hand wheel journaled on said upper crank arm, drive means operatively connected to said hand wheel and said combination wheel for selectively rotating said combination wheel when said hand wheel is rotated, a rod journaled in one of said beam members for pivotal movement relative thereto, a lateral extremity on said rod, a steering and supporting wheel rotatably mounted on said lateral extremity, means connecting said shaft and said rod for simultaneous pivotal movement.

SAMUEL DIMON.
